CLAIM

The ornamental design for a panel, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top plan view of a panel, showing my new design; and,

FIG. 2 is an enlarged detail view taken from the boxed area of FIG. 1.

The dash-dash broken lines represent boundaries of the claim and form no part of the claimed design. The dot-dash-dot broken lines represent the bounds of the enlarged view and form no part of the claim.
